UNITED STATES PATENT OFFICE

126,550

DESIGN FOR A CARPET OR SIMILAR ARTICLE

Augusta K. Bartholomew, New York, N. Y., and Francis M. Hirst, Philadelphia, Pa., assignors to Archibald Holmes & Son, Philadelphia, Pa., a corporation of Pennsylvania

Application February 10, 1941, Serial No. 93,900

Term of patent 3½ years

To all whom it may concern:

Be it known that Augusta K. Bartholomew and Francis M. Hirst, citizens of the United States and residents of New York city, New York, and Philadelphia, Pennsylvania, respectively, have invented a new, original, and ornamental Design for a Carpet or Similar Article, of which the following is a specification, reference being had to the accompanying drawing, forming part thereof, in which the figure is a plan view of a carpet showing our design.

We claim:

The ornamental design for a carpet or similar article, substantially as shown.

AUGUSTA K. BARTHOLOMEW.
FRANCIS M. HIRST.
